UNITED STATES PATENT OFFICE

FRANK A. WALD, OF LEMOYNE, PENNSYLVANIA

COOLING SYSTEM FOR INTERNAL COMBUSTION ENGINES

Application filed November 18, 1929. Serial No. 408,100.

This invention relates to cooling systems especially adapted for use in connection with internal combustion engines.

The invention forming the subject of this application contemplates reliable and automatic means by which the flow and velocity of cooling fluid through an internal combustion engine is controlled by, and is proportional to the temperature of the cooling fluid, to the end that a more uniform temperature of the entire cooling system is maintained. Among the other advantages of such a control of the flow of cooling fluid will be found increased velocity of such fluid at periods of operation when increased velocity is desired, a higher operating temperature which is conducive to fuel economy, a reduction in radiator area, less distortion of cylinder walls, and a diminished tendency for the walls of the fluid passages to become fouled with accumulations of scale and the like.

Another feature of the invention resides in the adaptability of the same to the cooling systems of engines without elaborate departure from present construction and operating methods, it being noted in this connection that the invention may be applied to an engine either during manufacture or at any time thereafter.

Other objects and advantages will be apparent during the course of the following description.

In the accompanying drawing forming a part of this application and in which like numerals are employed to designate like parts throughout the same,

Figure 1 is a fragmentary side elevation of an internal combustion engine equipped with the improved cooling system, parts of the former and latter being shown in section.

Figure 2 is a sectional view through a thermostat and associated valve, the view illustrating a constantly open by-pass for the circulation of the cooling fluid regardless of the position of the thermostat operated valve,

Figure 3 is a vertical sectional view through a relief valve embodied in the invention.

In the drawing wherein for the purpose of illustration is shown a preferred embodi-

ment of the invention, the numeral 5 designates an internal combustion engine, the cylinders of which are surrounded by a water jacket 6 through which a cooling fluid such as water is circulated. The water jacket 6 is shown to be adapted for communication with the header 7 of the radiator, by a pipe or hose connection 8, while the connection between the lower header or tank 10 of the radiator and the pump 9, is established by a hose connection 12. The usual outlet pipe 14 extends from the pump 9 into the water jacket of the motor at a convenient point.

The thermostat 14 intended to be positioned at or adjacent to the outlet from the water jacket 6 might now be said to be conventional and has connection with a valve 16 by which the flow of water from the engine to the header 7 is controlled. Such control is, of course, brought about by the temperature of the cooling fluid acting against the thermostat 14 with the result that a rise in the temperature to a predetermined value, such for example, as 135° will result in the movement of the valve 16 to open position.

When the valve 16 occupies an open position, the fluid passage thus produced is of sufficient cross sectional area to allow of the free flow of fluid under pressure from the pump 9.

A valve casing 20 is shown to be incorporated in the line of flow of the cooling fluid from the engine to the radiator and is provided with a valve element 22 having connection with a second thermostat 24 adjusted to respond to a temperature somewhat higher than that at which the thermostat 14 operates. For example it has been said that the thermostat 14 may be adjusted to open the valve 16 at approximately 135° Fahrenheit. Now, the thermostat 24 may be adjusted to open the valve element 22 at possibly 150° to allow of the greatest flow of fluid of which the system is capable.

The valve casing 20 is shown to be provided with a bypass 26 that may be in the nature of radial ports, which ports are constantly open to allow of a restricted flow of fluid at temperatures below that required to open the valve element 22.

It is important to observe that the fluid conducting capacity of the by-pass 26 is less than that of the fluid conducting passage associated with the valve 16, so that when the 5 thermostat 14 is open and the valve 22 has, as yet, remained unopened, the flow of cooling fluid, and consequently the velocity thereof, is restricted. With the valve 16 thus 10 opened the descent of the cooling fluid through the radiator is by gravity aided by the suction effect of the pump 9.

The invention forming the subject of this application contemplates a cooling system sealed or isolated from the atmosphere except when it is necessary to relieve an 15 normally high pressure resulting from the failure of some part of the system on the associated internal combustion engine.

In explaining the sealing feature, attention is invited to Figures 1 and 3 in which it 20 is illustrated that the vent pipe 40 extending into the header 7 has the inlet thereof controlled by a spring closed valve 42, the spring controlling the valve element 42 being of 25 sufficient power to resist the pressure increase incident to the opening of the valve 22 in response to a predetermined rise in the temperature, of the circulating cooling fluid. More specifically, the spring closed valve 42 30 may be arranged to open under the influence of steam generated as an incident to improper operation of some part of the system, such, for example, as the pump or driving means therefor.

By thus normally sealing the system, 35 changes in altitude will have no effect on the boiling point of the cooling fluid as distinguished from an open or vented cooling system in which the cooling fluid will boil at a 40 high altitude at a lower temperature than the same fluid would boil in the same open system at sea level or other low altitude.

Figure 1 illustrates that an expansion tank 45 60 may be attached to the dash or other convenient place on the car at a level preferably above that of the header 7. Communication is established between the expansion tank 60 and the fluid conducting means of the cooling system by a tube 62 which has, by way of illustration, been shown to communicate with the water jacket 6.

In operation, when the motor is operating 55 at normal load, the temperature of the cooling fluid will be of a value below that required to operate the thermostat 24 and the associated valve 22. Hence, there will be a restricted flow through the fixed by-pass openings, and, as previously suggested, the flow of cooling fluid through the tubes 30 will be by gravity 60 aided by the slight suction effect created by the pump 9.

Now, for the purpose of illustration, let it be assumed that the requirements on the motor are increased materially, such, for example as when the motor is required to propel

the vehicle on which it is mounted up a long steep grade with the throttle fully open or nearly so. The fulfillment of such a requirement is, of course, accompanied by an increase in the temperature of the cooling fluid, and this in turn, operates through the thermostat 24 to bring about the unseating of the valve 22 and the opening of the fluid passage previously closed, thereby permitting maximum velocity and flow of the cooling fluid through the casing 20 and in fact through the entire system.

The opening or unseating of the valve 22 will result in an increased pressure in the header 7 so that a greater volume of fluid is forced through the radiator core to the end that the return of the lower normal operating temperature is accomplished. Concurrently with the diminution in the temperature of the circulating fluid a retarded flow of circulating fluid will again prevail. The spring associated with the valve 42 is of sufficient strength to resist the pressure in the header 7 as a result of the unseating of the valve 22.

Thus, the automatically variable velocity of cooling fluid will be recognized as of value in preventing both overcooling and overheating of cooling fluid. Also, such automatic variation in the velocity of cooling fluid makes possible a reduction in radiator area, and hence, a higher temperature of fluid necessitating a higher velocity on the part of the fluid. The higher mean temperature of the cooling fluid has the effect of increased efficiency by reason of the lower fuel consumption.

Furthermore, the automatically variable velocity of the cooling fluid lends greater flexibility to a system which may be operated at a higher temperature with less difference in temperature of cooling fluid entering and leaving the engine jacket.

The air trapped in the tank 60 will serve as an air cushion providing for limited expansion of the cooling fluid as a result of temperature increases thereof, all without opening the system to the atmosphere.

Having thus described the invention, what is claimed is:

1. The combination of an engine having a jacket for a cooling fluid, a radiator having connection with said jacket, a thermostat having a valve controlling the flow of fluid between the jacket and the radiator, there being a constantly open by-pass allowing the flow of fluid between the jacket and the radiator, and a second thermostat between the first named thermostat and jacket responsive to a lower temperature than that at which the first thermostat operates, there being a valve associated with and operated by said second thermostat for controlling the entire circulation of cooling fluid.

2. The combination of an engine having a

jacket for a cooling fluid, a radiator having connection with said jacket, a thermostat having a valve controlling the flow of fluid between the jacket and the radiator, there being a constantly open by-pass allowing the flow of fluid between the jacket and the radiator, a second thermostat between the first named thermostat and jacket responsive to a lower temperature than that at which the first thermostat operates, there being a valve associated with and operated by said second thermostat for controlling the entire circulation of cooling fluid, and a vent pipe having a spring closed inlet located within said radiator and normally isolating the radiator and jacket from the atmosphere.

3. In a cooling system for internal combustion engines, a jacket adapted for the passage of a cooling fluid, a radiator, means establishing communication between said jacket and said radiator, a thermostat having a valve controlling communication between the jacket and the radiator, a valve casing having a constantly open by-pass providing constricted communication between said jacket and said radiator, a valve for said casing, and a second thermostat connected to said second named valve and responsive to a temperature higher than that at which the first named thermostat operates, there being pressure responsive means normally isolating the radiator and jacket from the atmosphere.

4. In a cooling system for internal combustion engines, a jacket adapted for the passage of a cooling fluid, a radiator, means establishing communication between said jacket and said radiator, a thermostat having a valve controlling communication between the jacket and the radiator, a valve casing having a constantly open by-pass providing constricted communication between said jacket and said radiator, a valve for said casing, and a second thermostat connected to said second named valve and responsive to a temperature higher than that at which the first named thermostat operates.

5. The combination of an internal combustion engine having a pump and a water jacket; a radiator in circuit with said jacket and said pump; heat responsive means for varying the velocity of the fluid traveling through the radiator and the water jacket; and releasable means including a vent pipe having its upper end disposed in the upper end of the radiator and its lower end arranged exteriorly of and below the radiator and opened to the atmosphere at said lower end, and a spring valve normally closing the upper end of the vent pipe for normally isolating the fluid passages through said radiator, said pump and said jacket from the atmosphere.

6. The combination of an internal combustion engine having a water jacket, a radiator

in circuit with said jacket and said pump, heat responsive means for varying the velocity of the fluid traveling through the radiator and the water jacket, and an expansion tank having a single connection with the water jacket and being out of the path of circulation of fluid through the jacket and the radiator.

7. In a radiator, upper and lower headers and tubes joining the headers, a vent pipe open at the lower end thereof to the atmosphere and having an inlet located within said upper header, releasable means normally closing said inlet and being responsive to the pressure within the upper header, and a heat responsive element throttling the flow of fluid through the radiator.

8. In a cooling system for internal combustion engines, a radiator having upper and lower headers and tubes joining the headers, and a vent pipe having an inlet within said upper header, said vent pipe extending below the upper header and being freely open at the lower end thereof to atmosphere, releasable spring pressed means normally closing said inlet and being responsive to the pressure prevailing within the upper header, a pump for circulating fluid under pressure through said radiator, and a heat responsive element throttling the flow of fluid through the radiator.

In testimony whereof I affix my signature.
